FILE DRAWER FACE PANEL

Joseph H. McCarthy, Youngstown, Ohio, assignor to The General Fireproofing Company, Youngstown, Ohio, a corporation of Ohio

Filed Jan. 10, 1964, Ser. No. 78,150

Term of patent 14 years

(Cl. D33—1)

FIG. 3.

FIG. 1.

FIG. 2.

FIG. 4.

FIG. 5.

FIG. 6.

FIG. 7.

FIG. 1 is a front elevation of the file drawer face panel, embodying my new design.

FIG. 2 is a side elevation of the file drawer face panel shown in FIG. 1.

FIG. 3 is a top plan view of the file drawer face panel shown in FIG. 1.

FIG. 4 is a partial perspective view of the file drawer face panel, embodying my new design.

FIG. 5 is a partial perspective view of the file drawer face panel shown in FIG. 4 and illustrates the pull handle in fully extended position.

FIG. 6 is a side elevation of the file drawer face panel similar to that shown in FIG. 2 and illustrates the pull handle in fully extended position.

FIG. 7 is a fragmentary vertical sectional view taken on the line 7—7 of FIG. 1.

The dominant features of my design reside in those portions shown in full lines on the drawing.

I claim:

The ornamental design for file drawer face panel, as shown and described.
